CONTROL WHEEL

James W. Downing, Los Alamitos, George R. Jansen,
Newport Beach, Richard L. Kauffman, Buena Park, and
Paul H. Patten, Playa Del Rey, Calif., assignors to
Douglas Aircraft Company, Inc., Santa Monica, Calif.

Filed June 29, 1964, Ser. No. 80,629

Term of patent 14 years

(Cl. D71—1)

Fig. 1

Fig. 2

Fig. 3.

Fig. 4.

Fig. 5.

FIG. 6.

FIG. 7.

FIGURE 1 is a perspective view taken from the front and side of a control wheel embodying our new design; FIGURE 2 is a front elevational view thereof;

FIGURE 3 is a side elevational view taken from the left side thereof;

FIGURE 4 is a side elevational view taken from the right side thereof;

FIGURE 5 is a top plan view thereof;

FIGURE 6 is a rear elevational view thereof; and

FIGURE 7 is a bottom plan view thereof.

The dominant features of our design reside in the portions shown in full lines.

We claim:

The ornamental design for a control wheel, substantially as shown and described.
